SHEET FEEDING MECHANISM FOR
ACCOUNTING MACHINES

Oscar J. Sundstrand, West Hartford, Conn., assignor to Underwood Elliott Fisher Company, New York, N. Y., a corporation of Delaware

Application June 3, 1940, Serial No. 338,509

8 Claims. (Cl. 197—130)

This invention relates to accounting machines, and more particularly to sheet feeding apparatus for the paper carriages thereof.

In performing public utility company billing operations on accounting machines, it is desirable to have the bills fed successively, one by one, to the platen for the printing of the data for each customer.

It is accordingly an object of the present invention to provide a paper feeding apparatus that is operable to automatically feed a sheet from a supply magazine to the platen, and after it is printed to feed it from the platen to a receiving magazine.

With this and incidental objects in view, the invention consists in certain novel features of construction and combinations of parts, the essential elements of which are set forth in appended claims, and a preferred embodiment of which is hereinafter described with reference to the drawings which accompany and form part of the specification.

In the drawings:

Figure 1 is a perspective view of a carriage embodying the invention,

Figure 2 is a right side elevation of mechanism that feeds a sheet from a supply magazine to belts that feed the sheets around the platen, the parts being shown in normal position.

Figure 3 is a view similar to Figure 2 but with the mechanism shown in position to pick up a sheet,

Figure 4 is a view similar to Figure 3 but showing a sheet picked up and ready for placement between the feed belts,

Figure 5 is a view similar to Figure 4 but showing the mechanism placing the sheet between the feed belts,

Figures 2a, 3a, 4a and 5a supplement Figures 2, 3, 4 and 5 respectively, each being a diagrammatic plan view of certain cams and rollers that control the actuation of the feed mechanism and each showing the position of the rollers with respect to the cams for the particular operation that is shown in the corresponding figure above,

Figure 6 is a diagrammatic top plan view of the carriage, illustrating the arrangement of appurtenant parts of the feed mechanism,

Figure 7 is a detail sectional view taken on the line 7—7 of Figure 6,

Figure 8 is a perspective view of a suction pump that produces vacuum to pick up the sheets,

Figure 9 is a fragmental front elevation of the supply magazine,

Figure 10 is a detail front view of one of the

vacuum cups which forms part of the feed mechanism,

Figure 11 is a detail right side elevation thereof, partly in section,

Figures 12, 13 and 14 are detail sectional views of the various feed belt pulleys,

Figure 15 is a detail left side view of a worm gear and a detent device which form part of the feed belt drive, and

Figure 16 is a detail sectional view taken on the line 16—16 of Figure 15.

The invention is illustrated in connection with the type of carriage used on the machine disclosed in U. S. Patent No. 2,194,270, issued to applicant on March 19, 1940.

Carriage in general

Referring to Figure 1, the carriage is mounted for movement along a track 1 upon rollers 2 (Figure 5) that lie between grooves 3 in the track and oppositely disposed grooves 4 in a frame 5. The carriage is arranged to be moved from right to left on what is known as its working stroke, under the drive of a suitable spring motor. During the working stroke the carriage is stopped in its several columns by suitable tabulating mechanism so that type bars 6 (Figure 1) on the accounting machine may print on the work sheets fed around the platen. When the carriage has reached the end of its working stroke, i. e., the position shown in Figure 1, a clutch (not shown) automatically becomes effective to return it to its initial position under power supplied by the accounting machine motor (not shown). The tabulating, clutch and driving mechanisms may be similar to those disclosed in the above-mentioned patent.

The carriage includes side walls 1 and 8 (Figure 1) secured on opposite ends of frame 5 (Figure 5). An auxiliary side wall 11 (Figure 1) is mounted adjacent wall 1 by suitable spacing collars and screws such as 12. Auxiliary wall 11 supports parts of the automatic feed mechanism, including a work sheet supply magazine now to be described.

Supply magazine

The supply magazine is indicated generally at 13 (Figures 1, 2 and 9). It comprises a base 14 having upstanding sides such as 15. The magazine is supported upon a pair of tie rods 16 and 17 extending between walls 8 and 11 and passing through sides 15. Collars 18 fixed on the rods adjacent sides 15 hold the magazine in place. A lip 21 formed along the right edge of base

14 provides a stop for the lower edge of the foremost sheet of a stack placed within the magazine. A follower, comprised of spaced plates 22 and 23 mounted for sliding movement on a plate 24, is arranged to bear against the rearmost sheet of the stack and provide a constant pressure upon the sheets, to thereby insure proper sheet feeding operations.

The intermediate plate 24 is supported in the magazine upon a pair of rods 25 having their opposite reduced ends extending through ears 26 formed on the opposite ends of the plate. Rollers 27 (Figures 4 and 9), mounted on the ends of rods 25, ride in angularly disposed slots 28 and 29 in sides 15, the slot 29 being offset slightly to the right to hold the follower assembly in the inclined position shown in Figure 2. The lower edge of plate 22 rests upon base 14.

When a sheet is removed from the magazine, plate 24, by gravity, descends a slight increment, moving plate 22 toward the right. This movement slides the stack bodily toward the right, and positions the foremost sheet against lip 21 for removal by feed mechanism now to be described.

Mechanism for feeding a sheet to the feed belts

The mechanism for removing a sheet from the supply magazine and placing it between belts that feed the sheets around the platen includes a pair of vacuum cups 31 (Figures 1 and 2). Cups 31 are fastened on the ends of tubes 32 supported in slots 32a (Figure 11) provided in flanges 33 formed on a pair of slides 34 and 35. Slides 34 and 35 are mounted on side walls 8 and 11, respectively, upon studs 36. The opposite ends of tubes 32 are fixed on brackets 43 pivoted on arms 41 which, in turn, are pivoted on studs 42 carried by slides 34 and 35.

A spring 44 encircles each stud 42, and has one of its ends hooked over its corresponding slide and its opposite end hooked over its corresponding arm 41. Springs 44 normally tension arms 41 clockwise around pivots 42, studs 45 secured in the arms and extending into slots 49 in the slides limiting the extent of clockwise movement. When arms 41 are so held, depending beveled projections 46 (Figure 11) formed on tubes 32 adjacent cups 31 lie in slots 32a, holding cups 31 elevated in the slots. Spring pulled detents 37 pivoted on walls 8 and 11 engage notches 38 in the slides, to hold the slides in their normal raised position shown in Figures 1 and 2.

The mechanism for controlling actuation of slides 34 and 35 and arms 41 includes a pair of levers 47 and 48 pivoted on studs 51 in walls 8 and 11 respectively. Levers 47 and 48 are connected for parallel uniform movement by tie rods 52. Each lever has an arm 53 carrying a stud 54 resting in a recess 55 in its corresponding slide 34 and 35. Each lever has also an upstanding arm 56 to which is pivoted one end of a link 57. The opposite ends of links 57 are connected by pin and slot connections 58 to arms 41. A depending arm on lever 47 carries a roller 61 arranged to engage a cam device. This device comprises a base plate 62 (Figure 6) fixed on track 1. To this base plate are fastened two plates 63 and 64 defining a cam track 60 between them. At the beginning of a carriage return stroke, roller 61 lies in the left end of the track as shown in Figures 1, 2a and 6.

Any suitable device may be provided to create vacuum within cups 31 for removing a sheet from the supply magazine. Herein is shown a

suction pump 65 (Figures 1, 2, 6 and 8) secured by a bracket 66 to wall 8. The pump comprises a piston cylinder within which is fitted a plunger 69 (Figure 8) carrying in the usual manner any suitable piston ring for a seal with the inner surface of the cylinder. Flexible tubing 70 connects tubes 32 with the chamber of the cylinder. The outer end of plunger 69 is loosely pivoted at 67 to an arm of a bell crank lever 68 loosely pivoted upon a shouldered stud 71 fixed on frame 5 (Figure 5). The opposite arm of lever 68 carries a roller 72 arranged to engage a cam plate 73 mounted on base plate 62 to the left of plates 63 and 64 (Figure 6). A spring 74 connected between lever 68 and frame 5 normally tensions the lever counter-clockwise about stud 71 and holds plunger 66 against the rear wall of the cylinder. A coil spring 75, encircling stud 71 between a cap on the stud and lever 68, holds the lever down against the shoulder of the stud.

When the carriage moves toward the right on its return stroke, rollers 72 and 61 simultaneously roll along the inclined edge of plate 73 and along track 60 respectively, from the position shown in Figure 2a to the position shown in Figure 3a. During this movement, plate 73 cams roller 72 and lever 68 clockwise (Figures 1 and 8) against the tension of spring 74, pulling plunger 69 from the cylinder chamber to start suction in cups 31. At the same time, track 60 cams roller 61 and levers 47-48 counter-clockwise, pulling links 57 toward the left. Links 57, in turn, pull arms 41, tubes 32 and cups 31 toward magazine 13 against the tension of springs 44, removing projections 46 from slots 32a, and thereby bringing the faces of cups 31 flush against the front sheet of the stack, as shown in Figure 3. The suction in cups 31 creates sufficient vacuum to hold the sheet firmly to the cups.

Continued return movement of the carriage moves rollers 72 and 61 from the positions shown in Figure 3a to the positions shown in Figure 4a. During this movement, plate 73 continues its camming action on plunger 69 to maintain the vacuum, whereas track 60 cams roller 61 and levers 47-48 clockwise, back to normal position (Figure 4). Coincidental rightward movement of links 57 permits arms 41, tubes 32 and cups 31 to restore under the tension of springs 44. During the restoring movement, slots 32a cam tubes 32 upwardly as projections 46 re-enter the slots, thereby raising cups 31 and lifting the sheet up and away from lip 21 as shown in Figure 4. In this position, the upper edge of the sheet lies beneath ears 76 formed on flanges 33.

As the carriage progresses on its return stroke, rollers 72 and 61 move from the positions shown in Figure 4a to the positions shown in Figure 5a. During this movement, plate 73 continues to cam the roller 72, maintaining the vacuum. Track 60, however, cams levers 47-48 further clockwise from the position shown in Figure 4 to the position shown in Figure 5. This further clockwise movement of levers 47-48, by virtue of studs 54 engaging the lower ends of recesses 55, thrusts slides 34 and 35 downwardly, placing the lower edge of the sheet between a pair of endless belts 78 and 81 at a point 82 where the two belts form a junction, ears 76 assisting cups 31 in lowering the sheet. Slides 34 and 35 are now held in their lower position by detents 37 engaging notches 77 therein. Shortly thereafter, when roller 72 passes beyond the inclined edge of cam 73, spring 74 restores plunger 69 to the position shown in

Figure 8, breaking the vacuum and releasing the sheet. At substantially the same moment that the sheet is released, mechanism described in the next section becomes operative to rotate the feed belts during the remainder of the return movement of the carriage, to carry the sheet downwardly between the belts toward the platen.

Feed belt mechanism

Two pairs of the endless feed belts 78-81 are provided, each pair being located adjacent the opposite ends of the carriage (Figure 1) and traveling over similar sprockets and pulleys mounted on walls 7, 8 and 11 and over the front of the platen. Driving belts 81 have perforations registering with pins 84 in sprockets 85 and 86 over which these belts travel. Lower sprockets 86 are mounted below the platen (Figure 1) on walls 7 and 8, as shown in detail in Figure 13. Upper sprockets 85 are fixed on a transverse shaft 87, as shown in detail in Figure 12. Shaft 87 extends through auxiliary side wall 11 (Figure 1) and is journaled at its opposite ends in side walls 7 and 8. Driven belts 78 lie over belts 81 and pass over and under rollers 88 and 89, thence upwardly, to the rear, around idler pulleys 92 (Figure 1) fixed on a transversely extending shaft 93, as shown in detail in Figure 14. The opposite ends of shaft 93 are journaled in bearings provided in walls 8 and 11. Belts are sufficiently taut against belts 81 to cause rotation therewith.

The means for rotating the belts comprises a gear 94, rotatably mounted between flanges 95 upon the lower end of a drive shaft 96 passing through the flanges. Flanges 95 are formed on a bracket 97 secured on side wall 7. The hub of gear 94 has an annular groove fitting within a slot provided in the upper flange 95. The upper face of the hub has beveled teeth 98 engaging correspondingly beveled teeth 99 on a collar 101 having a slot 102 embracing a pin 103 fixed in shaft 96. A spring 104, encircling shaft 96 between collar 101 and a pin 105 fixed in the shaft, normally holds teeth 98 and 99 in clutching engagement. The upper end of shaft 96 is journaled in a suitable bearing mounted in a flange 106 formed on bracket 97, and carries a worm 107 meshing with a worm gear 108 secured on the left end of shaft 87.

At substantially the same moment that a sheet is placed between belts 78 and 81 and released from cups 31 as above described, gear 94 meshes with the teeth of a rack 109 fixed on track 1 (Figures 1 and 6). Hence, as the carriage continues its rightward movement along track 1 to the end of its return stroke, gear 94 rotates clockwise, and through the clutch and worm gear connections, rotates shaft 87 and sprockets 85 counter-clockwise, driving belts 78 and 81 in counter-clockwise direction around the platen. The remaining return movement of the carriage is sufficient to advance the sheet just deposited, downwardly between the belts to a position behind the platen, and to simultaneously advance a sheet previously occupying this position around, under and upwardly into printing position in front of the platen. At the same time, a previously printed sheet moves upwardly between the belts away from the platen, toward a receiving magazine 112 secured between walls 8 and 11 on studs 113.

When the carriage moves toward the left on its next working stroke, gear 94 rotates counter-clockwise along rack 109. No movement is imparted to the feed belts, however, because a

spring-pulled detent 114 (Figures 1 and 15), pivoted on side wall 7 and engaging a notch in a disk 115 fixed on shaft 87, holds shafts 87 and 96 against reverse rotation, spring 104 being weaker than the spring on the detent and permitting beveled teeth 99 to declutch from and ride over teeth 98.

During the working stroke, roller 61 reenters track 60, and actuates its appurtenant parts in identically the reverse manner of their movements during the return stroke. As roller 61 moves leftwardly from the position shown in Figure 5a to the position shown in Figure 3a, levers 47-48 are cammed counter-clockwise from the position shown in Figure 5 to the position shown in Figure 3 and, by virtue of studs 54 engaging the upper ends of recesses 55, thrust slides 34 and 35 upwardly into normal position ready for the next sheet feeding operation. At approximately the same moment that roller 61 re-enters track 60, roller 72 rides upwardly over a depending beveled portion 116 formed on the right end of plate 73 (Figures 6 and 7), and continues to ride along the top surface of the plate during the remainder of the working stroke, the loose pivotal mounting of lever 68 on stud 71 and its loose pivotal connection with plunger 69 permitting this rising movement against the pressure of spring 75. Hence, no vacuum is created in cups 31 during the working stroke, and consequently the reverse movement of parts associated with roller 61 has no effect aside from the restoration of slides 34 and 35 above described.

When the carriage reaches the end of its working stroke, roller 72 drops to operative position in front of the inclined edge of plate 73, under the pressure of spring 75, and roller 61 rests in the left end of track 60, as shown in Figure 1, ready for the next feeding operation on the succeeding return stroke.

While the form of mechanism herein shown and described is admirably adapted to fulfill the objects primarily stated, it is to be understood that it is not intended to confine the invention to the one form of embodiment herein disclosed, for it is susceptible of embodiment in various forms all coming within the scope of the claims which follow.

What is claimed is:

1. In a machine of the class described, a traveling carriage movable through working and return strokes, a platen, a supply magazine for holding a stack of work sheets, means controlled by the carriage and operating during each return stroke of the carriage, for removing a work sheet from the magazine and means also controlled by the carriage and operating during each return stroke for moving the removed work sheets toward and around the platen.
2. In a machine of the class described, a traveling carriage movable through working and return strokes, a platen, a supply magazine for holding a stack of work sheets, means controlled by the carriage and operating during each return stroke of the carriage, for removing a work sheet from the magazine, and conveyor means also controlled by the carriage and operating during a later part of each return stroke of the carriage, for moving the removed work sheets toward and around the platen.
3. In an accounting machine, a transversely movable paper carriage, a supply magazine on the carriage for holding a stack of work sheets, suction means operated by the carriage during its travel, for removing the sheets from the

magazine and a conveyor means also operated by the carriage for moving the removed work sheets toward the platen.

4. In an accounting machine, a transversely movable paper carriage, a supply magazine on the carriage for holding a stack of work sheets, a suction cup for removing the work sheets from the stack, and means operated by the carriage during its travel for providing the necessary suction.

5. In a machine of the class described, a traveling carriage movable through working and return strokes, a platen, a supply magazine for holding a stack of work sheets, conveying means, means controlled by the carriage and operable during a portion of the return stroke to transfer a sheet from the stack to the conveying means, and means also controlled by the carriage and operable during another portion of the return stroke to operate the conveying means to advance a removed sheet toward the platen.

6. In a machine of the class described, having printing mechanism and a traveling carriage provided with a platen, the traveling carriage being movable in opposite directions, a supply magazine for holding a stack of work sheets, sheet feeding mechanism to carry the sheets toward and away from the platen, means controlled by the carriage and acting during a portion of the carriage travel in one direction to transfer a sheet from the stack to the sheet feeding mechanism, and means controlled by the carriage and acting during another portion of the carriage travel in the same direction to operate the sheet feeding mechanism to move the transferred sheet toward the platen, and to move a previously transferred sheet past the platen.

7. In a machine of the class described, having printing mechanism and a traveling carriage supporting a platen and movable through working and return strokes, a magazine for supporting a stack of work sheets, a pair of feed belts, having a point of entry therebetween, for carrying the work sheets to the platen, suction means including a cup movable to and from the stack, and thence toward the point of entry, an actuator supported on the carriage and connected with the cup, and means on a stationary part of the machine for operating said actuated to cooperate with the suction means in moving a sheet from the stack to the point of entry, during the return stroke.
- 10 5 15 20 25 30 35
8. In a machine of the class described, having printing mechanism and a traveling carriage supporting a platen and movable through working and return strokes, a supply magazine for supporting a stack of work sheets, a receiving magazine for supporting the work sheets, a pair of feed belts having a point of entry therebetween and defining an endless path past the printing point of the platen between the supply and receiving magazines, suction means including a cup movable to and from the stack, and thence toward the point of entry, an actuator supported on the carriage and connected with the cup, means on a stationary part of the machine for operating said actuator to cooperate with the suction means in removing a sheet from the stack to the point of entry, during a portion of the return stroke, and means operable during another portion of the return stroke to move the belts an extent sufficient to advance the removed sheet toward the platen.

OSCAR J. SUNDSTRAND.
